UNITED STATES PATENT OFFICE.

LAWRENCE O. BEARD, OF LANCASTER, PENNSYLVANIA.

VALVE-REFACING TOOL.

Application filed October 9, 1926. Serial No. 140,613.

My invention relates to improvements in valve refacing tools, and is more particularly directed to that type of tool adapted to reface worn or imperfect valves of an internal combustion engine.

The object of my invention is to provide a simply and economically constructed device which can be readily used by the average car owner or unskilled mechanic.

Another object is to provide simple and efficient means for adjusting and securing the cutter blade within the cutter head.

Other and more specific objects and advantages of my invention will be apparent as the specification is considered in connection with the accompanying drawing, in which:

Figure 1 is a top plan view of the tool;

Figure 2 is a bottom plan view of the same;

Figure 3 is a side elevation;

Figure 4 is a section on the line 4—4 of Figure 3;

Figure 5 is a detail view of the cutter blade.

Figure 6 is a sectional view taken on the line 6—6 of Figure 5, and

Figure 7 is a modified form of the cutter bar wherein both edges of the bar may be utilized as a cutting face.

Referring more particularly to the drawings, 1 denotes what may be termed a cutter head, substantially conical in shape and formed at its apex with a cylindrical internally threaded boss, 2. The cutter head is also formed with a slot 3 in which a cutter blade 4 is adjustably mounted in a manner hereinafter described. The blade 4, as disclosed in the drawings, is composed of a steel bar 1, the longitudinal edge of which has a beveled edge 4' which constitutes the cutting face and upon which a valve face is adapted to rest in a manner hereinafter described. Furthermore, it will be noted that the width of the cutter is substantially greater than the thickness of the cutter head. The valve stem 5 of a valve 6, which the operator desires to reface, is guided in the central bore 8 of a guide bushing 9, which is in turn threadedly mounted in the threaded bore 19 of the cylindrical boss 2 of the cutter head. The blade 4 also functions to clamp and lock the guide bushing in place and at the same time is supported by the bushing.

In adjusting the cutter blade to proper

cutting position the blade is inserted in the slot 3 with the cutting face 4' of the blade substantially flush with the inner convex face 10 of the cutter head and the other face of which projects outwardly of the outer or concave face 11 of the cutter head. A pair of headed screws 12 screwing into threaded openings 13 formed in the concave face 11, are next screwed home until the screw heads, 60 which overlap the slot 3, engage the outer face of the blade adjacent opposite ends thereof and move the blade inwardly transversely of the slot, until the cutting edge of the blade protrudes through the slot the desired distance. As the respective convex and concave faces 10 and 11 are parallel and disposed at an angle of forty-five degrees to the axis of the tool, it is a comparatively simple matter for the user to readily determine 70 when the blade is in proper cutting position by merely placing the forefinger and thumb against the respective faces. After the blade has been positioned as to depth, screw 14 threadedly mounted in threaded opening 15 formed in the rim 16 of the cutter head, is screwed home until the head of the screw 75 engages the beveled outer end portion 17 of the blade and holds the blade against longitudinal movement within the slot 3 and with its lower end substantially flush with the threaded bore 19 of the boss 2, it being noted that the inner end of the slot 3, opens into the bore 19. At the same time during the 80 inward movement of the cutting blade its end engages the bushing 9, thus locking the same firmly in place. The lower end of the valve stem guide bushing is slightly beveled so that the bushing will readily clear the beveled corner 21 of the blade and engage 85 the beveled inner end portion 18 thereof.

In practice the user inserts the stem 5 of the valve 6 down through the guide opening or bore 8 in the valve stem guide bushing 9 until the valve engages or rests upon the cutter blade. The cutter head and valve are then relatively rotated with respect to each other by grasping the stem in a vise and the rim of the cutter head with the right hand, and manually, imparting opposing rotary movement to these parts. During this operation the valve is preferably pulled downwardly against the blade with considerable force to increase the cutting action of the blade.

As disclosed in Figure 7, I have illustrated a modified form of the cutting blade and in

which it will be noted that both ends of the blade are cut upon the same angles, thus permitting the insertion of the blade within the cutter head so that either end may engage the bushing, thus presenting a new cutting surface upon the cutting edge of the blade to be engaged by the work. In this form it will be evident that the life of the cutter will be increased and that its periods of 10 sharpening will be very few. Furthermore, when the blade is reversed end to end, a new cutting surface is always presented to the work, excepting at such times when the work engages the intermediate portion of the 15 blade.

Having thus described my invention what I claim is:

1. A valve refacing tool comprising a cutter head having an elongated slot therein, 20 a cutter blade adapted for insertion in said slot, headed screws on opposite sides of said slot, the heads of said screws adapted to hold and guide said blade in said slot, and means for locking the cutter blade in said 25 slot.

2. A valve refacing tool comprising a

conical cutter head having an elongated slot therein closed at its inner end and open at its outer end, a cutter blade adapted to seat at one end on the inner end of said slot, the other end of said blade projecting out through the outer open end of said slot, a screw positioned at one side of said slot and formed with a head for engaging the outer end of said blade for adjusting said blade 35 longitudinally of said slot, and means for guiding said blade during said adjustment.

3. A valve refacing tool comprising a conical cutter head having an elongated slot therein, a cutter blade adapted for insertion in said slot, headed screws on the opposing concave and convex faces of said cutter head and on opposite sides of said slot, the heads of said screws adapted to engage and hold and guide the blade in said slot, certain of 40 said screws also adapted to adjust the blade longitudinally of the slot, and certain of said screws adapted to adjust the blade transversely of the slot and means for locking the blade in desired adjusted position. 50

In testimony whereof I affix my signature.

LAWRENCE O. BEARD.
